ALEXANDER BECK, OF PHILADELPHIA, PENNSYLVANIA.

A.

Design No. 2,616, dated April 16, 1867.

DESIGN FOR A CARPET PATTERN.

The Schedule referred to in these Letters Patent and making part of the same.

TO ALL WHOM IT MAY CONCERN:

Be it known that I, ALEXANDER BECK, of Philadelphia, county of Philadelphia, State of Pennsylvania, have invented or produced a new and original Design for a Carpet Pattern; and I do hereby declare that the accompanying drawing, and the following explanation thereof, form a full, clear, and exact description of the said design.

The view in the drawing represents a section of carpet or floor-cloth, the central figure A representing a spray of leaves and flowers, and adjacent to this figure are ornamental figures B B C C, one-fourth only of each of which is illustrated in the drawing.

I claim the design for the pattern of a carpet or floor-cloth, substantially as shown in and by the accompanying drawing.

In testimony whereof I have signed my name to this specification in the presence of two subscribing witnesses.

Witnesses:

H. HOWSON,

W. J. R. DELANY.
